UNITED STATES PATENT OFFICE.

LAVINIA D. RICHARDSON, OF FREDERICKSBURG, VIRGINIA.

POCKET ASH-RECEPACLE.

No. 820,067.

Specification of Letters Patent.

Patented May 8, 1906.

Application filed June 22, 1905. Serial No. 266,511.

To all whom it may concern:

Be it known that I, LAVINIA D. RICHARDSON, a citizen of the United States, residing at Fredericksburg, in the county of Spotsylvania and State of Virginia, have invented new and useful Improvements in Pocket Ash-Receptacles, of which the following is a specification.

My invention relates to a novel device to be used by smokers, and comprises a hollow elastic receptacle provided with an aperture which is normally closed, but which may be readily opened by pressure on the body of the receptacle to enable the ashes from the end of a cigar or cigarette to be deposited within the receptacle and which will automatically close when the pressure is removed, so as to prevent the ashes from falling or sifting out.

The device will ordinarily be made of rubber and by preference will be fashioned to simulate the appearance of an animal, fish, reptile, or the like, the opening of the receptacle also serving as the mouth of such fish, animal, or reptile, so that on squeezing the device to cause the lips of the opening to be separated an effect will be produced resembling more or less accurately the action in life of the creature represented opening its mouth.

The device is intended to be carried in the pocket, and when it is desired to knock the ash from the cigar or cigarette it is taken in the hand and squeezed, the ash deposited in the receptacle, and the latter returned to the pocket.

My invention thus presents a novelty affording more or less amusement in use and also tending to promote cleanliness about the person and the immediate vicinity of the smoker, besides affording an essentially useful device and one always at hand for the purpose intended.

I have illustrated my invention in the accompanying drawings, in which—

Figure 1 is a perspective view of the device in its normal position. Fig. 2 is a similar view showing the device partly compressed to cause the opening or mouth to be distended, and Fig. 3 is a longitudinal sectional view.

As shown in the drawings, the device is fashioned to simulate in appearance a swell-

fish or sea-porcupine, the body 1 being hollow and serving as a receptacle for the ash and being provided with an opening 2, which is also coincident with the mouth of the fish. As shown by Fig. 2, when the body 1 is compressed by the fingers on the sides the mouth 2 will be caused to open to permit the ash to be discharged within the receptacle, this action of separating the lips of the opening 2 very closely resembling, as stated above, the action of the fish in life in opening its mouth. As a means of amusement, principally for children, this action of compressing the sides of the device can be repeated at short intervals, and thus more nearly approximate the well-known action of a fish in drawing in water. The device as a whole may be suitably painted or otherwise colored to carry out the lifelike representation of the fish, or, as shown by Fig. 3, a suitable covering 3, of felt or other similar material, may be provided.

In order to prevent the slit or opening 2 from extending farther than is intended in the use of the device, I preferably reinforce said opening by means of thickening the edges thereof, as indicated at 4.

While I have indicated the purpose of the device to be that of a receptacle for cigar or cigarette ashes, it will be apparent that the same could be used for carrying small change or sold to children filled with candy. Many other similar uses or applications of the device will be obvious.

Having thus fully described my invention, what I claim as new, and desire to secure by Letters Patent, is—

A device of the class described fashioned to simulate a living creature, comprising a unitary hollow elastic body substantially circular in cross-section and provided with a slit in its wall serving as the mouth of such creature, said body being otherwise imperforate, said slit being reinforced about its edges and being normally closed and adapted to be opened by compressing the walls of said body.

In testimony whereof I have hereunto set my hand in presence of two subscribing witnesses.

LAVINIA D. RICHARDSON.
